UNIVERSAL COLD ROLL FORMING MACHINE

Robert C. P. Kane, Syracuse, N. Y.

Application June 6, 1940, Serial No. 339,111

19 Claims. (Cl. 153—54)

My invention relates to improvements in cold roll forming machines adapted to bend a sheet of metal into tubes or other formed shapes which may be of a desired cross sectional contour.

One of the objects of this invention is to provide a machine adapted progressively to form a flat metal sheet into a tube or other shape having a desired cross sectional contour, in such a manner as to avoid excessive working of the metal, especially adjacent the longitudinal edges thereof.

Another object of this invention is to minimize the internal stresses set up in the formed shape and to distribute any stresses so produced substantially equally or uniformly.

Still another object of this invention is to form the blank in such manner as to minimize lineal elongation of the metal.

When progressively forming sheet metal into a tube, there is a tendency of the tube to run off from the straight in a direction away from the side where the edges of the blank are formed over to meet. The usual practice is to form the tube with the seam uppermost, the tube curves downwardly as it leaves the forming rolls, because the edges of the blank have been worked more than the center, resulting in at least some elongation of the material adjacent these edges. Likewise, in forming shapes other than tubes, where the contour is non-symmetrical, in cross sectional contour, there is a tendency to run off laterally toward the side of the shape on which the lesser amount of work has been performed. The amount of runoff will vary with the shape formed, with different thicknesses of metal and also with metal of different temper in different lots.

Another object of this invention is to produce a cold roll forming machine of the above mentioned class consisting of various units for forming, welding, sizing, straightening, etc., with movable supports for certain or all of the units whereby such units may be adjusted with respect to each other for bringing the work, during the process of producing a finished article, into operative relation with successive units after it passes from the forming unit without bending or twisting the work or subjecting portions of the same extending between the units to external stresses or pressures.

In carrying out the above mentioned objects, I have provided a machine having a forming unit composed of a plurality of pairs of forming rolls spaced longitudinally of the machine to provide a sufficient number of roll passes and wherein

the contours of the rolls of successive passes are so correlated as to gradually change the shape of the metal as the same is fed through the forming unit from one pass to the next. Furthermore, the rolls of each roll pass are mounted for vertical adjustment with respect to the rolls of the other passes so that the longitudinal central portion of the tube or other article being formed may be progressively moved in one direction away from the plane of entry of the flat material into the forming unit without the production of abrupt bends or kinks in the material.

Another object of the invention is to so mount the rolls of each pass of the forming unit that at least one roll thereof may be adjusted horizontally with respect to the other roll of the same pass or substantially parallel with the direction of travel of the work through the unit whereby the work will move through each roll pass substantially normal to a straight line connecting the axes of the rolls thereof.

Other objects and advantages pertaining to the construction and operation of the parts of my forming machine will more fully appear from the following description taken in conjunction with the accompanying drawings, in which:

Figure 1 is a plan view illustrating a forming machine and a driving mechanism associated therewith embodying the various features of this invention.

Figure 2 is a side elevation of the forming machine illustrated in Figure 1.

Figure 3 is a detail transverse vertical sectional view taken substantially on line 3—3, Figure 2, illustrating the mechanism for producing vertical adjustment of the forward end portion of the forming unit.

Figure 4 is a detail vertical sectional view taken on line 4—4, Figure 3.

Figure 5 is a detail vertical transverse sectional view taken substantially on line 5—5, Figure 2, illustrating the mechanism for producing vertical adjustment of the rear end portion of the forming unit.

Figure 6 is a detail vertical sectional view taken on line 6—6, Figure 5.

Figure 7 is a detail horizontal sectional view taken on line 7—7, Figure 6.

Figure 8 is a detail horizontal sectional view taken on line 8—8, Figure 3.

Figure 9 is a vertical sectional view taken substantially on line 9—9, Figure 3, illustrating a forming roll assembly of one of the roll passes of the forming unit in side elevation, a portion thereof being broken away and in section.

Figures 10, 11 and 12 are detail horizontal sectional views taken respectively on lines 10—10, 11—11 and 12—12, Figure 9, the forming roll associated with the shaft shown in Figure 12 being omitted.

Figure 13 is a detail horizontal sectional view taken on line 13—13, Figure 2, illustrating a pivotal connection for the forward end of one of the base members of the apparatus.

Figure 14 is a side elevation illustrating a portion of a modified form of the forming unit.

Figure 15 is a detail transverse sectional view taken substantially on line 15—15, Figure 14.

Figure 16 is a detail longitudinal central sectional view through the base portion of the mechanism illustrated in Figure 14, illustrating the manner of cradling or rocking the forming unit illustrated in Figure 14.

Figure 17 is a transverse sectional view similar to Figure 15 illustrating a modified form of support for a forming roll pass.

Figure 18 is a detail vertical sectional view taken substantially on line 18—18, Figure 17.

Figure 19 is a detail transverse sectional view similar to Figures 15 and 17, illustrating a still further modified mounting for the forming roll passes.

In order to illustrate my invention, I have shown in Figures 1 and 2 of the drawings a machine adapted to completely form a tube or pipe from a strip or sheet of flat rolled metal. This machine comprises a forming unit 1, a welding unit 2, a scarfing unit 3, a cooler 4, a sizer unit 5, a straightening unit 6 and a cut-off unit 7. These units are arranged in spaced relation to each other longitudinally of the machine and in the order named for successively receiving the metal and performing their various functions thereon. These units are supported by a main or sub-base 9 which is common to all of the units.

Mounted on the sub-base 9 are two base members 10 and 11 which are adjustably supported by the sub-base 9 for tilting movement with respect thereto. The base member 10, in this instance, is carried by an auxiliary base 12 mounted intermediate the base members 9 and 10 upon the former base member. The auxiliary base 12 has end portions 13 and 14 thereof slidably engaging bearing portions 15 and 16 formed on the upper surface of the sub-base 9. The auxiliary base 12 is pivotally connected at its rear end to the sub-base 9 by a pin 17 engaging in a suitable aperture provided in an extension 18 formed on the rear end portion 14 of the auxiliary base 12.

The pin 17, as illustrated more particularly in Figure 13, is secured to a supporting block 19 which is slidably mounted in a recess 20 formed in the upper portion of the base 9 transversely thereof. The ends of the recess 20 are closed by plates 21 and the block 19 and pin 17 are adapted to be adjusted longitudinally through the recess 20 transversely of the base 9 by screws 22 screw-threaded in the plates 21 with the inner ends thereof contacting the adjacent end portions of the block 19.

The forward end of the auxiliary base 12 is provided with an extension or tongue 24 which projects forwardly from the base between a pair of lugs 25 formed on the base 9 in spaced relation to each other transversely of said base, as illustrated in Figure 1. The lugs 25 are provided with screws 26 which are adapted to en-

gage the tongue 24 for producing lateral movement of the forward end portion of the auxiliary base 12 with respect to the base 9. It will be understood that when the forward end portion 5 of the auxiliary base 12 is moved laterally with respect to the base 9, said auxiliary base will swing about the pin 17 as an axis while the position of the pin 17 and, therefore, the axis of swinging movement of the auxiliary base 12, may be adjusted transversely of the sub-base 9, as the occasion may require, by the manipulation of the screws 22.

The base member 10 is spaced upwardly from the auxiliary base 12 and is adjustably connected 15 with the auxiliary base so that the ends thereof may be moved vertically with respect to the auxiliary base and independently of one another. The means for operatively connecting the base 10 with the auxiliary base 12 comprises two pairs of jack screws 29 and 30, the jack members 29 being located at the rear or inner ends of the base members 10 and 12, while the jack members 30 are located adjacent the forward or outer ends of said base members. The base member 10, in this instance, has the rear portion 10' thereof extended above the forward portion 10'' and the portion 10' supports the welding, scarfing, cooling and the sizing units in fixed predetermined spaced relation to each other. The forward portion 10'' of the base member 10 has mounted thereover a platform 32 which is adapted to carry the various roll passes of the forming unit 1.

The platform 32 is adjustably connected with 35 the base 10 to be supported in vertical spaced relation thereto by two pairs of jack members 29 and 30 arranged adjacent the rear and forward ends respectively of the platform. The jack members 29 positioned at the rear or inner ends of the platform 32, base 10 and auxiliary base 12 are constructed substantially alike and a description of one of these jack members will suffice for a description of the others.

Each jack member 29 connecting platform 32 45 with base 10 comprises a vertically disposed screw member 34 which, as shown in Figures 5 and 6, has the upper end thereof extending through an elongated slot 35 provided in a pendent marginal flange 36 formed along each longitudinal side of the platform 32. The upper end of the screw member 34 is secured to a horizontally disposed pin 37 which is journaled in a suitable opening provided in the corresponding flange 36. The screw members 34 of each pair of jacks 55 29, as indicated in Figure 5, are arranged adjacent the longitudinal sides of the platform 32 and base member 10 and extend downwardly from the platform through suitable openings 38 provided in the side walls 39 of the base member 10. Each screw member 34 is provided with a nut 40 screw-threaded thereon and which is positioned in a transversely disposed recess 41 provided in the base 10 intermediate the upper and lower ends of the corresponding openings 65 38. Each nut member 40 has the peripheral surface thereof provided with worm gear teeth 42 which have meshing engagement with a worm 43 mounted on a shaft 44.

The shaft 44 is disposed in a horizontal plane 70 transversely of the base member 10 and is journaled in suitable bearing members 45 provided on a laterally disposed portion 46 of the side walls 39, as indicated in Figures 6 and 7. There are two bearing members 45 for each worm 43,

the bearing members of each pair being spaced longitudinally of the shaft and receive the corresponding worm between them for maintaining said worm against axial movement during the rotation thereof. Each end of shaft 44 extends outwardly beyond the adjacent side wall 39 of the base 10 and has secured thereto a hand wheel 48 by which the shaft may be manually rotated from either side of the base 10.

It will now be observed that rotation of the shaft 44 will produce a corresponding rotation of the worms 43 and nut members 40 and inasmuch as the nut members 40 are maintained against axial movement by the adjacent walls of the recesses 41, rotation of said nut members will produce corresponding vertical movements of the screw members 34 in an upward or downward direction depending upon the direction of rotation of the nut members. The upward and downward movement of the screw members 34 will of course produce a corresponding movement of the rear or inner end of the platform 32 with respect to the base member 10.

As hereinbefore stated, the jack members 29 connecting the base member 10 with the auxiliary base 12 are constructed in substantially the same manner as the jack members just described for connecting the platform 32 with the base 10. It will be understood, however, that the pins 37 and upper ends of the screw members 34 are rotatably connected with the base 10 while the lower portions of the screw members 34, the nut members 40 and worms 43 are associated with the auxiliary base 12 so that rotation of said worm and nut members will produce vertical movement of the screw members 34 and base member 10 with respect to the auxiliary base 12.

As shown in Figures 3 and 4, the jack members 29 connecting the outer or forward end portion of the platform 32 with the base member 10, each comprises a vertically disposed screw member 50 having the upper end thereof extending through an elongated recess 51 provided in the lower side of the flange 36 of the platform 32. The upper end of each screw 50 is connected, as shown in Figure 3, with a horizontally disposed pin 53 which is journaled in a suitable opening 54 provided in the corresponding flange 36. Each screw member 50 extends downwardly from the platform 32 through a corresponding elongated opening 56 formed in the respective side wall 39 of the base 10.

Each side wall 39 of the base 10 is provided with a relatively large cylindrical opening 58 extending inwardly from the outer side thereof and which is arranged with the center thereof passing through the center of the opening 56 at substantially right angles thereto. In each opening 58 is journaled a relatively large hollow cylindrical bearing member 60 having diametrically disposed apertured bosses 61 receiving a corresponding screw member 50 therethrough. Each bearing member 60 is releasably maintained in the opening 58 therefor by a suitable annular retaining plate 63 secured to the outer face of the side wall 39 by screws 64, as shown in Figures 3 and 8.

Mounted upon each screw member 50 and positioned intermediate the corresponding bosses 61 is a nut 67 having screw-threaded engagement with the screw member 50. The peripheral surface of each nut member 67 is provided with worm teeth 68 which are in meshing engagement with a suitable worm 69 mounted on a horizon-

tally disposed shaft 70. Each worm 69, as shown more particularly in Figure 8, is mounted between a pair of lugs 71 provided on the corresponding bearing member 60 in right angular relation to the bosses 61. These lugs 71 are provided with aligned openings which rotatably receive the shaft 70 therein. The ends of the shaft 70 extend outwardly beyond the adjacent bearing member 60 and have secured thereto hand wheels 73 by which the shaft may be manually rotated from either side of the base 10. It will now be understood that rotation of the shaft 70 will produce corresponding rotation of the nut members 67 which, in turn, produce corresponding vertical movement of the screw members 50. The jack members 30 connecting the base member 10 with the auxiliary base 12 are constructed and operated in the same manner as the jack members 29 just described for connecting the platform 32 with the base member 10 with the exception, of course, that the bearing members 60 instead of being mounted in the base 10 are mounted in the auxiliary base 12, while the pins 53 associated with the upper ends of the screw members 50 are connected with the base member 10 instead of with the platform 32.

It will now be observed that inasmuch as the screw members 34 of the jacks 29 are mounted for vertical reciprocative movement only in the base 10 or base 12, the pins 37 associated therewith will provide relatively fixed axes about which the base member 10 or platform 32 associated therewith will swing during the vertical adjustment of the screw members 50 associated with the jacks 30. It therefore follows that during this swinging movement of the forward or outer end of either the base member 10 or platform 32, the screw members 50 of the corresponding jacks 30 will rock about the axes of the bearing members 60 and produce a corresponding rocking movement of said bearing members in their openings 58.

In order that the end thrust produced on the platform 32 during the operation of the forming unit 1 may not be transmitted solely to the screw members 34 of the jacks 29, I have provided a buffer plate 75 which is secured to the rear portion 10' of base 10 and extends upwardly from said base into engagement with the adjacent end of the platform 32. The rear end of the platform may be curved, as at 76, in concentric relation with the pins 37 so that said platform will uniformly contact with the buffer plate 75 at all vertical tilted positions thereof produced by the manipulation of the jacks 29 and 30. In a similar manner, the base member 10 may be provided with a buffer member 77 connected with the rear portion of the sub-base 9 and which projects upwardly therefrom into engagement with the forward end of the base 10. The rear end of the base 10, as indicated at 78, may be formed concentric with the adjacent pins 37 of the jacks 29 associated therewith so that said end will have uniform engagement with the buffer 77 during all vertical tilted positions of the base 10 produced by the jacks 29 and 30 connecting said base with the auxiliary base 12.

The base member 11 is mounted over the rear end portion 9' of the sub-base 9 and, as shown in Figures 1 and 2, has mounted thereon the straightener unit 6 and the cut-off unit 7. The base 11 is shown supportably connected with the sub-base 9 by means of jack members 29 and 30 constructed and operated in the same manner as the jack members 29 and 30 hereinbefore

described connecting the base 10 with the auxiliary base 12 or the platform 32 with the base 10.

As illustrated in Figure 2, the jack members 29 are arranged adjacent the rear ends of the bases 9 and 11 while the jack members 30 are arranged adjacent the opposite or inner end of the base 11. The nut members 40 and 67, together with the worms 43 and 69 and their shafts 44 and 70, are connected with the upwardly extended portion 9' of the sub-base 9 which may be formed integral with said sub-base or secured thereto. The extension 9' of the sub-base may, as illustrated in Figure 2, be provided with a recess 79 at the inner end thereof for receiving the pivotal pin 17 and extension 18 therein. It will be understood that the opposite ends of the base member 11 may be raised or lowered independently of each other relative to the base 9 by the manipulation of the jacks 29 and 30.

The welder 2, scarfer 3, cooler 4, sizer 5, straightener 6 and cut-off 7 may be of any suitable construction and, as indicated in Figure 2, these various units are fixedly secured to their respective base members 10 or 11 in predetermined spaced relation to each other. The forming unit 1 may, as shown, be provided with a table 80 which is secured to the outer or forward end of the platform 32 for supporting the sheet metal, as M, from which the tube, pipe or other article is formed.

The forming unit also comprises a suitable number of roll passes, as indicated at A, B, C, D and E arranged in spaced relation to each other longitudinally of the platform 32 at the rear of the table 80. The passes A, B, C and E each constitute a stand of opposed rolls, and these rolls of the several passes are adapted to form the flat rolled metal M into a transverse curved form on arcs of decreasing radii. The rolls of passes A, B, C and E may be driven by any suitable means such as the motor 81, Figure 1, through the medium of a suitable speed reduction gearing indicated at 82, and power transmission mechanisms 83 mounted on a common base 84 positioned at the rear side of the sub-base 9 in substantially parallel relation therewith.

The transmission mechanisms 83 are preferably connected with the rollers of the passes A, B, C and E by extensible shafts 85 composed of telescoping sections and which are connected with the corresponding roll shafts and transmission shafts by suitable universal joints, indicated at 86, Figures 1 and 3, so that the shafts of the rolls may be adjusted as required by movement of the bases 10 and 12 and of the platform 32 without materially decreasing the efficiency or producing special adjustments of the transmissions 83.

The shafts 85 of the drive mechanism may, as indicated in Figure 3, be connected directly with the shafts 88 of the lower positioned forming rolls of the corresponding passes while the shafts 89 of the upper positioned rolls of said passes may be operatively connected to the shafts 88 of the corresponding pass by a pair of spur gears 90 mounted on the shafts 88 and 89 in meshing engagement with each other.

The housings of each roll pass A, B, C and E are substantially identical in each case, the contour of the rolls being the only essentially different feature. The housing, as 92, which supports rolls 93 and 94 of the first pass A, which rolls are positioned laterally by means of collars 93' and 94' respectively, comprises a substantially

vertically disposed standard 96 which is secured to an auxiliary base plate 97 by means of bolts 98 mounted in T-slots 99 extending longitudinally of the base plate 97. The bolts 98 extend upwardly through flanges 96' formed at the base of each standard 96 at the inner and outer sides thereof. The T-slots 99 which extend longitudinally through the auxiliary base plate 97 are arranged transversely of the platform 32 so that the standards 92 may be adjusted with respect to the base plate 97 toward and from each other axially of the shafts 88 and 89. The auxiliary base plate 97 is slidably mounted upon the upper face of the platform 32 for movement longitudinally of said platform.

In order that the auxiliary base plate may be maintained against movement transversely of the platform, there is provided a key 100 which is mounted in suitable key slots provided in the adjacent surfaces of the base plate 97 and platform 32, as indicated in Figure 3. The base plate 97 is secured in the adjusted position thereof by means of studs 102 which pass upwardly through elongated openings provided in the platform 32 and screw-threaded into the base plate 97, as illustrated in Figure 3. Suitable washers, as 103, may be mounted on the studs between the heads thereof and the adjacent portion of the platform for limiting the movement of the studs through the platform slots.

Each standard 96 is provided with a recess 105 extending from the upper end thereof downwardly for receiving the bearing blocks 106 and 107 for the lower and upper roll shafts 88 and 89, respectively. Each standard is provided with a cap 108 which extends across the upper end thereof over the recess 105 and is secured to the standard by suitable tie-rods 109 and nuts 109', as illustrated in Figure 9. The bearing blocks 107 for the upper roll shaft 89 are of less width than the recess 105 and have the opposed vertical sides thereof extending in substantial parallel relation to each other and at an angle of inclination to the upper and lower sides of the block, as indicated at 110, Figure 9.

Each bearing block 107 is supported from the cap 108 by a bracket 111 with the upper and lower sides of the bearing block arranged substantially normal to the vertical sides of the recess 105. The bracket 111 is secured to the corresponding bearing block 107 for lateral adjustment with respect thereto by screws 112 passing through an elongated slot 113 in bracket 111. Bracket 111 is supported by the cap 108 of the corresponding housing through the medium of a positioning screw 114 having screw-threaded engagement with the cap, said screw being provided with a head 115 at the lower end thereof which is received in a T-slot 116 provided in a cap 117 secured to the upper side of the bracket 111 by a pair of screws 118.

The T-slot 116 extends across the cap 117 for a purpose presently to be described. Interposed between each bearing block 107 and the vertical side walls of the recess 105 are two block shims 119 which are supported by the bracket 111 by means of positioning screws 120 screw-threaded in the upper ends of the block shims and rotatably carried by a plate 121 secured to the bracket 111. The block shims 119 are wedge-shaped members having the inner surfaces 119' thereof inclined with respect to the vertical to correspond to the inclined side surfaces 110 of the bearing block 107.

It will now be observed that the bearing block

107 may be moved transversely of the standard recess 105 by adjusting the block shims 119 vertically with respect to the bracket 111 by rotating the screws 120. In other words, if the bearing block illustrated in Figure 9 is to be moved toward the right-hand side of the standard, the block shim 119 at the right-hand side of the bearing block may be lowered with respect to the bracket 111 by turning the screw 120 associated therewith in the proper direction. After the block shim 119 at the right-hand side of the bearing block has been lowered the proper distance, the bearing block 107 is loosened from bracket 111 by turning screws 113. The block shim 119 at the opposite or left-hand side of the bearing block may next be lowered by the manipulation of the screw 120 associated therewith until the bearing block is moved laterally the required distance and firmly held between the block shims to position the upper shaft 89 and the roll carried thereby in such relation to the lower shaft 88 and the roll carried by said latter shaft, that the work engaged by the rolls will move substantially normal to a straight line connecting the axes of shafts 88 and 89.

The bearing block assembly comprising the bearing blocks 107, block shims 119 and brackets 111 may be adjusted vertically as a unit through the recess 105 by the manipulation of the positioning screw 114 to bring the roll carried by 30 the shaft 89 into proper spaced relation with the roll carried by the lower shaft 88 for forming the material M as the same is moved between the rolls.

The bearing block 107 associated with the standard 96 located at the driving end of the rolls 93 and 94 may, as shown in Figure 12, be provided with guide flanges 107' arranged at opposite sides thereof. These flanges are spaced from each other a distance substantially equal to the width of the standard 96 and the block shim 119 for receiving said standard and block shim therebetween and maintaining the bearing block against axial movement with respect to the standard. The bearing, as 122, mounted in the bearing block 107 having the flanges 107' is preferably of such a type and so mounted between a pair of cap members 123 and 124 secured to the opposite sides of the bearing block and a shoulder 125 and nut 126 on shaft 89 that said bearing member and shaft will be maintained against axial movement with respect to the bearing block.

The shaft 89, as shown in Figure 12, is composed of two sections, a roll bearing section 89' and a drive section 89'' which are secured together by a union nut 127 having engagement with a flange 127' secured to the section 89' in screw-threaded engagement with the inner adjacent end of the other section 89''.

The bearing block 107 which supportably engages shaft section 89' is a plain member maintained against axial movement with respect to the shaft 89 by the roll nut 128 and screw-thread 128' located at the outer end of the shaft 89', the bearing sleeve 107a and spacing collars 94'.

When it is desired to remove the shaft 89' from the housing, the nut 128 is backed off and the entire assembly 107 including bracket 111 and shims 119 may be pulled out. Shaft section 89' is disconnected from the shaft section 89'' by disengaging the nut 127 from the threaded portion of said latter shaft section, after which

the shaft section 89' may be readily moved axially through the housing recess 105.

If, on the other hand, it is desired to remove both sections 89' and 89'' from the housing 92, 5 this may be readily accomplished without disconnecting the shaft sections 89 and 89'' by swinging the cap members 108 about one of the tie-rods 109, as the one shown at the right-hand side of Figure 11, after having loosened the nuts 109' associated with both of said rods and sliding the entire assembly upwards out of the standard 96. In order that the caps 108 may be readily swung about one of the tie-rods, each cap is provided with a slot 131 adjacent one end for receiving the tie-rod therein and arranged substantially concentric with the other tie-rod, as illustrated in Figure 11.

As a cap 108 is thus swung about one of the tie-rods, the positioning screw 114 will move therewith through the recess 116 out of cooperative engagement with the cap 117 provided on the bracket 111. After a cap 108 has thus been moved to one side of the recess 105, the upper roll assembly, including the shaft 89, bearing blocks 107, block shims 119 and brackets 111, may be lifted bodily from the standards 96 by passing the same upwardly through the recesses 105.

The bearing blocks 106 for the lower positioned shafts 88 are mounted, as shown in Figure 9, at the lower end of the respective recess 105. These bearing blocks are maintained in predetermined spaced relation to the bottom of the recesses 105 and to the side walls of said recesses by suitable shims 132 and 133, respectively. By using the side shims 133, it will be observed that the lower shafts 88 may be adjusted laterally of the recesses 105 so as to bring the lower forming roll carried thereby in such relation to the roll carried by the upper shaft 89 that the metal passing between the rolls will be positioned substantially normal to a direct line joining the axes of said upper and lower shafts, providing the action of the block shims 119 is not sufficient to produce this result.

45 A limiting screw 135 may also be mounted in the lower end of each standard 96 beneath the lower bearing block 106, as illustrated in Figure 9, to assist in obtaining the accurate positioning of the lower bearing blocks 106 and the shaft 88 carried thereby before inserting the bottom shims 132 beneath the bearing blocks.

55 While I have illustrated but four forming passes and one idler or side roll pass in the forming unit shown in Figures 1 and 2, it will be understood that the number of passes and their over-all length may be varied as required, and the forming rolls of the various passes may be of any desired contour to produce an article of manufacture from flat sheet metal. When forming tube or pipe blanks, it is preferable to so position the top and bottom rolls of each pass vertically that as the metal advances through the machine from one set of rolls to the next, the central portions of the metal which are gripped by the respective rolls progressively are at greater distances from the center line of the metal on table 80 so that the bending occurs smoothly, gradually and progressively. The smooth, substantially continuous bending of the metal eliminates excessive stretching of the metal adjacent longitudinal edges thereof as said edges gradually approach each other. This absence of stretching of the metal stock not only materially reduces residual strains and crumpling of the edges but also results in the tube

being formed more readily and with a minimum consumption of power.

However, when tubes or other articles of manufacture are formed by bending flat metal stock in this manner, the article very often tends to deflect or curve laterally as it emerges from the forming unit due to variations in the thickness of different portions of the stock and to changes in the degree of temper thereof. This results in it being difficult to feed the tube from one unit into another without the application of external pressure to the tube to offset the lateral deflection of the tube.

It therefore follows that either the forming unit and the welder must be spaced from each other such a distance that the tube may be overflexed laterally in a direction opposite to the deflection thereof and then permitted to return to the normal course of the tube in alignment with the opening of the second unit, or provisions must be made to hold the tube against the stresses tending to deflect the same in a lateral direction.

In applicant's device, the roll pass D may be adjusted laterally of the forming unit platform 32 to so position the tube with respect to the welder that the tube will freely enter said welder even though having a tendency to deflect to one side of the normal path of movement thereof through the machine. If the tube tends to deflect vertically then the forming unit may be correspondingly adjusted to compensate for this deflection by the manipulation of the jacks 29 and 30 connecting the forming unit with the base member 10 so that the tube will freely enter the welder.

As the tube passes through the welder unit 2, the seam edges of the tube are welded to each other in the usual manner. During the welding of the seam edges of the tube the portions of the metal adjacent said edges become heated to a greater extent than the remaining or opposite side portion of the tube. This results in the upper portion of the tube expanding to a greater extent than the lower portion thereof so that the tube, when leaving the welder, tends to deflect downwardly, as indicated by the portion *a* of the dot-and-dash line A—A in Figure 2 which indicates the normal path of movement of the article as it is being formed during the movement thereof through the various units of the forming machine. As the tube enters the cooling unit 4 and the upper and lower portions of said tube again return to substantially the same degree of temperature, the upper portion of the tube will contract to a greater extent than the lower portion thereof so that the tube again tends to curve upwardly, as indicated at *a'*.

After the tube leaves the cooler 4, it enters the sizer 5. In order that the tube will readily enter between the rollers of the sizer 5 the forming unit 1 may be adjusted by manipulating the jacks 29 and 30 connected therewith so that the tube entering the welder unit 2 will be at such an inclined angle to the horizontal that when it emerges from the cooler unit 4, the tube will travel in substantially a horizontal plane and will readily pass through the sizer unit 5 without undue stresses produced therein or stretching of the wall thereof.

As the tube moves beyond the sizer unit 5, it is brought into the straightener unit 6 and this straightener unit, and the cut-off unit associated therewith may be adjusted by the manipulation of the jacks 29 and 30 connecting the supporting base 11 for the units 6 and 7 with the sub-base 9

so that these units may be brought into proper vertical alignment with the tube for performing their respective functions on the tube in an easy normal manner. If the tube leaving the sizing unit 5 should tend to deflect laterally in substantially a horizontal plane, the tube may be readily brought into proper aligned relation with the rolls of the straightening unit 6 by adjusting the auxiliary base 12 with respect to the sub-base 9 about the pin 17 by the manipulation of the screws 26 in the manner hereinbefore described.

In Figures 14 to 18, inclusive, I have illustrated modified forms of the forming unit. These modifications are particularly useful in compensating for the twisting tendencies of work being formed to non-symmetrical cross sectional contour. Such work may have a tendency to run off at an angle to the forming rolls. By providing means to tilt the roll stands, the work may be brought into alignment with subsequent stands, or operation units without the use of extra means for forcing the work into proper alignment.

In the structure shown in Figures 14, 15 and 16, the platform, as 140, for supporting the roll passes of the forming unit 1 is provided with a pair of transversely disposed ribs 141 arranged near the ends thereof, as indicated in Figures 14 and 16, each of these ribs being provided with an arcuate channel 142 in the upper surface thereof arranged substantially concentric with the work passing through the roll passes adjacent thereto.

Mounted over the platform 140 in spaced relation thereto is a base plate 143 which supports the roll passes A, B, C, D and E thereon. The base plate 143 is provided with a pair of pendent flanges 144 having the lower surfaces thereof curved to correspond to the curvature of the channel 142. These flanges constitute rockers for supporting the base plate 143 and are positioned in the channels 142 to be supported by the ribs 141 and to slide through said channels. The base plate 143 is also provided with a pendent gear segment 145 which, as shown in the drawings, is positioned substantially midway between the flanges 144.

The lower edge surface of the segment 145 is curved to correspond to the curvature of the lower edges of the rockers 144 and is provided with gear teeth 146 which are in meshing engagement with a worm 147 mounted on a shaft 148. The shaft 148 extends transversely of the platform 140 and has the end portions thereof journaled in the side walls 149 of the platform, as illustrated in Figure 15. The outer ends of the shaft 148 extend a short distance beyond the side walls 149 and have secured thereto hand wheels 150 by which the shaft may be manually rotated.

The housings 92 for the roll passes may be secured directly to the base plate 143 or, as illustrated in the drawings, these housings may be connected directly to an auxiliary base plate 97 in the manner hereinbefore described for the housing members 92 shown in Figures 1, 2 and 9. These auxiliary base plates may be mounted upon the base plate 143 for longitudinal movement with respect thereto and be clamped to said base plate as by screws 102 and washers 103, as shown more particularly in Figure 3.

It will now be observed that when the auxiliary base plates 97 are clamped to the base plate 143, said base plate and all of the roll passes connected therewith may be rocked with respect to the platform 140 about an axis extending substantially co-incident with the axis of the work

being formed in the forming unit. This rocking of the forming unit will of course produce a corresponding rocking movement of the work carried thereby so as to maintain work with its top surface uppermost even though the work twists to a certain degree after it leaves the forming unit.

In Figures 17 and 18, I have illustrated a support for the forming unit whereby each of the roll passes may be rocked independently of each other. In the structure shown in these two figures, the forming unit platform, as 154, has mounted upon the upper surface thereof a plurality of supporting frames 155, one for each roll pass. These frames are each provided with a substantially rectangular base plate 156 which is splined to the platform 154 by a key 157 extending longitudinally of the platform. Each frame is clamped to the platform, as by screws 152 and washers 103, in the manner shown and described for the structure illustrated in Figure 3.

Each frame 155 is provided with a pair of upwardly projecting flanges or ribs 159 which have the upper surfaces thereof concaved and provided with channels 160 which are curved longitudinally of the flanges with the center of curvature thereof lying substantially coincident with the axis of the work engaged by the forming rolls of the corresponding pass.

Mounted over each frame 155 is an auxiliary base plate 162 to which a respective roll pass standard 92 is secured. Each of the auxiliary base plates 162 is provided with a pair of pendent segmental ribs 163 having the lower edges thereof curved to correspond to the curvature of the recesses 160 and positioned in said recesses for movement with respect to the flanges 159.

Each auxiliary base plate 162 is provided with a pendent segment 165 arranged intermediate the flanges or rockers 163. The lower edge of the flange 165 is curved to conform to the curvature of the lower edges of the rockers 163 and has provided thereon gear teeth 166 which are in meshing engagement with the worm 167 provided on a shaft 168. The shaft 168 extends from one side of the frame 155 to the other side thereof transversely of the platform 154 and has the end portions thereof journaled in suitable upwardly extending bearing elements or bosses 169. Hand wheels, as 170, are secured to the outer ends of the shaft 168 whereby the shaft may be manually rotated.

In the structure shown in Figures 17 and 18, it will be seen that any one of the roll passes provided with the auxiliary base plate 162 and frame 155 may be rotated independently of the remaining passes through the medium of the shaft 168, worm 167 and segment 165 to bring the forming rolls carried thereby from a normal vertical position to a position in inclined relation to said normal position for procuring a corresponding rotary movement of the portion of the work engaged by the rollers of said pass.

In Figure 19, I have shown a still further modified form of my invention which combines the features illustrated in Figures 15 and 17. In the structure shown in Figure 19, the platform, as 175, carried by the jacks 29 and 30 is provided with a pair of ribbed members 176 constructed similar to the rib members 141 shown in Figure 16.

Mounted over the platform 176 is a base plate 177 having a pair of rockers 178 adapted to be slidably supported by the ribs 176. The platform 177 is also provided with a segmental pendent rack member 179 which is in meshing

engagement with the worm gear 180 mounted on the shaft 181 carried by the platform 176. The shaft 181 is provided with hand wheels 182 at the ends thereof by which the shafts may be manually rotated for producing rocking, tilting movement of the base plate 177.

Mounted on the base plate 177 is a supporting frame 183 which, similar to the frame 155, is provided with a pair of upwardly extending ribs or flanges 184 having the upper surfaces thereof provided with a curved recess similar to the recess 160 provided in the ribs or flanges 159 shown in Figure 18. There is one frame 143 provided for each roll pass and mounted over each frame is an auxiliary base plate 185. This base plate 185 is constructed similar to the auxiliary base plate 162 shown in Figure 18 and is provided with a pair of pendent flanges or rockers 186 which slidably engage in the recesses provided in the ribs 184 for supporting the auxiliary plate over the frame 183. The auxiliary base plate 185 is provided with a pendent segmental rack 188 which has the teeth thereof in meshing engagement with the worm 189 provided on the shaft 190 rotatably supported by the frame 183. The shaft 190 is provided with hand wheels 191 by which said shaft may be rotated to produce tilting movement of the auxiliary base plate 185.

In the structure shown in Figure 19, it will be obvious that by rotating the shaft 181 and worm 180 the base plate 177 and all of the roll passes connected therewith will be tilted with respect to the platform 175. When it is desired to produce tilting movement of one or more of the roll passes with respect to the remaining roll passes and the platform 175, this may be readily accomplished by rotating the shaft 190 and the worm 189 connected therewith.

It will be obvious that each of the platforms shown in Figures 14 to 19, inclusive, may be supported by jacks 29 and 30 in the manner hereinbefore described for the platform 36 associated with the forming unit 1. When these platforms are supported by the jacks 29 and 30, it will be evident that the forming unit associated therewith may be adjusted vertically at each end independently of the vertical adjustment of the other end thereof for producing a corresponding change in the direction of movement of the work through the forming unit in addition to the rocking, tilting action of one or more of the roll passes. Furthermore, it will be evident that mechanism for producing a rocking, tilting action of the forming unit 1 may be readily applied to any one or number of the remaining units of the forming machine.

Although I have shown and particularly described the preferred embodiments of my invention, I do not wish to be limited to the exact construction shown as it is obvious that various changes, both in the form and relation of the parts thereof may readily be made without departing from the spirit of the invention as set forth in the appended claims.

I claim:

1. In a machine of the class described having a plurality of forming units adapted to cooperate to produce a tube or the like from a flat strip of metal, in combination, a base member, means connecting the forming units with the base member for maintaining said units in cooperative predetermined spaced relation to each other whereby they successively perform their respective functions, said means including a platform connected with one of the forming units and movable with

respect to the base, adjustable connecting means including a mechanism having vertically movable supporting members for moving said platform and said forming unit toward and away from the base, and separate supporting means including rock members connected with the forming unit and functioning independently of said vertically movable members for swinging said forming unit about an axis extending substantially coincidental with the longitudinal center of the work being formed.

2. In a forming machine of the class described having a plurality of forming units, a base member, an auxiliary base member, means pivotally connecting the auxiliary base member with said first mentioned base member whereby said auxiliary base may swing about a fixed axis, a forming unit connected with the base member to be directly supported thereby, a second forming unit mounted on the auxiliary base member in cooperative relation with the first mentioned unit, and means for swinging said auxiliary base about the fixed axis thereof to bring the forming unit carried thereby into different angular positions with respect to the first mentioned forming unit.

3. In a forming machine of the class described having a plurality of forming units, a base member, means connecting the forming units with the base member whereby said units are maintained in cooperative predetermined spaced relation to each other for successively performing their respective functions, said means including a supporting element connected with one of the forming units and movable with respect to the base, and jack members connected with the supporting element and with the base for producing vertical movement of said supporting element and the unit carried thereby with respect to the base while maintaining said units in said cooperative substantially predetermined spaced relationship.

4. A forming machine as set forth in claim 3 wherein at least one of said jack members is provided with a lifting screw mounted for vertical movement only with respect to one of said members and pivotally connected to the other of said members, a second jack member provided with a lifting screw, and means pivotally connecting said latter lifting screw with both of said members.

5. A forming machine as set forth in claim 3 wherein at least one of said jack members is provided with a lifting screw mounted for vertical movement only with respect to one of said members and pivotally connected to the other of said members, a second jack member provided with a lifting screw, means pivotally connecting said latter lifting screw with both of said members, and means associated with the base and supporting members for limiting the pivotal movement of the supporting member with respect to the base member in one direction.

6. In a forming machine of the class described having a plurality of forming units, means for supporting said forming units in cooperative predetermined spaced relation to each other for successively performing their respective functions comprising a sub-base, means connecting at least one of the forming units with said sub-base, a second base member directly connected with another of said forming units, means connecting the second base member with the sub-base including an auxiliary base pivotally connected with the sub-base to swing about a predetermined axis, and adjustable members connecting the sec-

ond base members with the auxiliary base member for swinging said second base member in a direction substantially normal to the first mentioned swinging movement thereof to bring the unit carried by said second base member into different angular relationship with the first mentioned forming unit.

7. In a forming machine of the class described having a plurality of forming units, means supporting said units in cooperative relation with each other comprising a base member supportably connected with one of said units, a second base member connected with the second one of said units, means pivotally connecting the base members to each other whereby the second base member may swing about a predetermined axis to bring the unit carried thereby into different angular positions with respect to the first forming unit, and means for producing said swinging movement of the second base member including a screw element, means pivotally connecting the screw element with one of said base members, and separate means pivotally connecting the screw element with the other of said base members including a bearing member rotatably supported by said latter base member, a nut member carried by said bearing member having screw-threaded engagement with the screw element, and means carried by the bearing member for rotating said nut member.

8. In a machine for forming a tube by progressively bending a flat piece of metal into a cylinder, a forming unit provided with a plurality of bending passes, each of said passes having a pair of forming rolls mounted in cooperative relation with each other for receiving the metal between them, means for producing movement of the rolls of each pass in a direction substantially normal to the path of movement of the sheet metal between the rolls to bring the space between the rolls into different positions at one side of the plane of entry of the material into the forming unit, and separate means for producing movement of the rolls of each pass with respect to each other longitudinally of the direction of movement of the material between the rolls for maintaining the path of movement of the material substantially normal to a straight line connecting the axes of rotation of said rolls.

9. A forming machine of the class set forth in claim 8 wherein said last mentioned means comprises a shaft for one of said rolls, bearing blocks for said shaft movable toward and from the direction of movement of the material, said bearing blocks having opposed sides thereof inclined with respect to said movement of the blocks, and means movable with respect to the bearing blocks and engageable with said inclined sides thereof for producing movement of the bearing blocks and the shaft carried thereby in a direction substantially normal to the first mentioned direction of movement of said bearing blocks and shaft.

10. In a forming machine of the class described having a series of roll passes for progressively bending a flat strip of metal to form a tube or bar of predetermined cross sectional contour, at least one of said roll passes having a pair of forming rolls mounted in cooperative relation with each other for receiving the metal between them, shafts for said rollers, means for supporting said shafts including a housing member, bearing blocks supported by said housing member and engageable with opposite end portions of the shafts, the shaft for one of said rolls being com-

posed of two sections, means releasably connecting said shaft sections to each other, and means releasably maintaining the bearing block associated with one of said sections with the housing member whereby said bearing member and the shaft section connected therewith may be removed from the housing member by axial move-

ment thereof when said shaft sections are disconnected from each other while maintaining the second shaft section in the housing member in cooperative relation with the shaft of the other roll.

ROBERT C. P. KANE.
